CARPET.

No. 20,763.

Patented May 19, 1891.

20,763 to 20,767, inclusive.—CARPET.—Paul Pignot, Hastings, assignor to *The Alex. Smith & Sons Carpet Company*, Youkers, N. Y. Applications filed April 22, 1891. Serial Nos. 390,049 to 390,053, inclusive. Term of patents 3½ years.

UNITED STATES PATENT OFFICE.

PAUL PIGNOT, OF HASTINGS, ASSIGNOR TO THE ALEX. SMITH & SONS
CARPET COMPANY, OF YONKERS, NEW YORK.

DESIGN FOR A CARPET.

SPECIFICATION forming part of Design No. 20,763, dated **May 19, 1891.**

Application filed April 22, 1891. Serial No. 390,049. Term of patent $3\frac{1}{2}$ years.

To all whom it may concern:

Be it known that I, PAUL PIGNOT, a citizen of the United States, residing at Hastings, Westchester county, New York, have invented 5 a new and original Design for Carpets, of which the following is a specification, reference being had to the accompanying photograph, which forms a part of the same.

The invention relates to a design to be 10 worked into or upon surfaces such as carpets or similar fabrics; and it consists in the novel configuration and grouping of figures herein specifically shown and claimed.

The accompanying photograph is a face 15 view of a carpet, showing my new design.

My design consists of the body A and the border B. The body A consists of groups of shaded flower, leaf, and stem forms upon a

ground of contrasted shading. The border B consists of groups of shaded flower, leaf, and 20 stem forms upon a ground of contrasted shading, of an inner ornamental margin, and of an outer margin.

What I claim, and desire to secure by Letters Patent, is—

1. The design for carpets, consisting of the body A, substantially as shown.
2. The design for carpets, consisting of the border B, substantially as shown.
3. The design for carpets, consisting of the 30 body A and the border B, substantially as shown.

PAUL PIGNOT.
